UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

VALVE-BAG-FILLING MACHINE.

1,248,061.

Specification of Letters Patent. Patented Nov. 27, 1917.

Application filed February 15, 1915. Serial No. 8,203.

To all whom it may concern:

Be it known that I, ADELMER M. BATES, a citizen of the United States, residing at Chicago, in the county of Cook and State 5 of Illinois, have invented a certain new and useful Improvement in Valve-Bag-Filling Machines, of which the following is a specification.

My invention relates to improvements in 10 bag filling machines, and has for one object to provide means for removing the filled bag from the filling relation, and discharging it to a conveyer or suitable means for disposing of it. Means for discharging or 15 moving are preferably operated by the hand of the operator.

I have illustrated those parts of a bag filling machine particularly adapted to filling valve bags, although it is obvious that 20 other means for actuating the discharge or removing device may be used, and the device might be applied to other types of bag filling machines.

My invention is more or less illustrated 25 diagrammatically in the accompanying drawings, wherein—

Figure 1 is a side elevation in part section.

Fig. 2 is a section along the line 2—2 of Fig. 1.

Fig. 3 is a diagrammatic front elevation 30 of part of the machine.

Fig. 4 is a diagrammatic side elevation in part section of a portion of the machine to show more clearly the relation of the parts.

Like parts are indicated by the same letter 35 in all the figures.

A is a supply hopper, A¹ a supply passage leading therefrom adapted to permit the passage of material to the propeller housing 40 A², from which the material is projected by the propeller wheel A³, through the feeding throat A⁴ into and through a bag filling tube A⁵. All the parts except the tube A⁵ are fixed in relation.

B is a scale beam. At its outer end it has a knife edge B¹, upon which rests an A frame B². The A frame is supported on the scale B, and guided at its top by the link B³, pivoted on the hopper A. This 45 A frame B² supports the filling tube A⁵, and has pivotally mounted thereon a bag holding latch B⁴ serrated at its lower end in engagement with the bag B⁶ as it hangs upon the tube A⁵. B⁶ is a trip lever pivoted

on the latch B⁴, free to swing with respect 55 to the latch in the direction opposite to the direction in which the latch itself is free to swing.

C is a cradle having an L-shaped bottom C¹, whose outer end is pivoted as at C² on the A frame B². C³ is a bag chair adjustable along the cradle C, by means of the pin C⁴, which may be made to engage in one of the notches C⁵ in the cradle itself. C⁶ is a breast-strap or plate surrounding a 60 portion of the bag, and so positioned that, as the bag hangs normally in the filling position, its inner side just touches this strap. C⁷ is a dumping handle attached to the upper end of the cradle C by means of which 65 the operator may easily manipulate the cradle.

D is a bag releasing wiper immediately 70 below the handle C⁷. It is adapted to engage the lever B⁶ when drawn out to tilt 75 the bag latch B⁴, and when thrust back, adapted to ride over such lever to permit free return of the parts to their previous position without interference with or by the bag latch.

It will be evident that while I have shown 80 in my drawings an operative device, still many changes might be made in size, shape and arrangement of parts without departing materially from the spirit of my invention.

Attention is called to my copending application Serial Number 4097, filed January 25, 1915, which shows an arrangement somewhat similar to that illustrated in the present application. Certain novel features shown but not claimed in this application 90 are claimed in that one.

The use and operation of my invention 95 are as follows:—

The bag is first suspended upon the filling tube with the parts in the position shown in Fig. 1, the lower portion of the bag resting upon the chair. The material is then discharged into the tube until the bag is 100 filled. When the bag is filled, the scale then operates in any suitable manner, or the feed supply is cut off in any suitable manner, neither of which is here illustrated, and the operator is then prepared to discharge 105 the bag. He does it by seizing the handle and giving it a smart pull toward him. As it moves, it first exerts pressure on the bag,

then releases the bag holding latch, and then discharges the bag. The point is that the breast strap first applies pressure to the bag at the upper end to tip it out away from its filling position, and that the chair is then tipped up and out to throw the bag. The result is that the bag is thrown into the position shown in dotted lines in Fig. 1 where it may rest upon the conveyer or plat-
 5 form, as indicated, and it is effectually thrown away from any position in which it might interfere with the weighing or the manipulation of the bags. The chair may be moved up and down to accommodate for
 10 varying lengths of the bag, and by this ar-
 15 arrangement, the heavy, stiff and rough bags are evenly and rapidly discharged without injury to the operator's hands, and without delay or danger of tearing the bag.
 20 The cradle is pivoted to the A frame at a point in front of the center of gravity of the bag, so that as the cradle is rocked, it tends to lift the bag from below, and when the operator jerks it smartly the breast-plate
 25 first rocks the bag from above and the chair catapults it from below and tips or swings it so as to throw it clear away from the ma-
 chine.

In Fig. 4 the cradle is shown in a position
 30 which it would never occupy merely for the purpose of making clear its shape and arrangement. The operator will, under or-
 35 dinary circumstances, never carry it any farther than in the position shown in dotted lines in Fig. 1, but of course it is free to move clear down should this become nec-
 essary or desirable.

It will be understood that by my arrange-
 40 ment I first rotate the package about its base by means of a package moving mem-
 ber, which, as noted, is immediately below the filling tube or fixed package support, and then I bodily throw the package up-
 45 wardly and forwardly, thus completing its rotation and permitting or causing it to draw into a position of rest at right angles to and altogether removed from that position which it originally occupied, and my movable package support at the bottom acts
 50 as a catapult to project or throw the bag away from its original position, so that it assumes the subsequent position.

I claim:

1. In a package filling machine a fixed
 55 package support and means for locking the package thereupon, a pivotally mounted cradle having a movable package support, a package moving member, and a lock releasing member all carried thereby.
2. In a package filling machine a fixed
 60 package support, a pivotally mounted cradle, a movable package support, and a package moving means, both carried thereby.
3. In a package filling machine a fixed
 65 package support and means for locking the

package thereupon, a pivotally mounted cradle having a movable package support, a package moving member, and a lock releasing member all carried thereby, said cradle being pivoted at a point forward of the cen-
 70 ter of gravity of the loaded cradle.

4. In a package filling machine a fixed package support, a pivotally mounted cradle, a movable package support, and a package moving means both carried thereby, said
 75 cradle being pivoted at a point forward of the center of gravity of the loaded cradle.

5. In a package filling machine a fixed package support, a pivotally mounted cradle, a movable package support, and a package
 80 moving means both carried thereby, said package moving means being adjacent the package support and adapted to draw the package from the support.

6. In a package filling machine a fixed package support and means for locking the package thereupon, a pivotally mounted cradle having a movable package support, a package moving member, and a lock releasing member all carried thereby, said mov-
 85 able support being adjustably mounted on the cradle.

7. In a package filling machine a fixed package support, a pivotally mounted cradle, a movable package support, and a pack-
 95 age moving means both carried thereby, said movable support being adjustably mounted on the cradle.

8. In a package filling machine means for holding the package in a substantially vertical position, means for releasing it and swinging it about a line perpendicular to its axis and means for simultaneously bodily throwing it upwardly and outwardly.

9. A package filling machine comprising a filling tube adapted to enter the package, means for locking the package in position thereon, a support for the lower end of the package, a pivoted frame carrying said support, means carried by it for withdrawing the package from the filling tube and means for releasing the package locking means.

10. A package filling machine comprising a filling tube adapted to enter the package, a support for the lower end of the package, a pivoted frame carrying said support, and means carried by said frame for withdrawing the package from the tube.

11. A package filling machine comprising a filling tube adapted to enter the package, means for moving the package laterally along the tube away from the filling relation, and simultaneously operated means engaging the bottom of the package for throwing it upwardly and outwardly to discharge it from the machine.

12. A package filling machine, an A frame, a package filling tube upon which the pack-
 120 age is mounted, a cradle pivoted on the frame, means for supporting the bottom of

the package on the cradle, and means carried by the cradle for withdrawing the package from the filling tube.

13. A package filling machine, an A frame, a package filling tube upon which the package is mounted, a cradle pivoted on the frame, means for supporting the bottom of the package on the cradle, means carried by the cradle for withdrawing the package from the filling tube, means for locking the

package on the filling tube, and means carried by the cradle for releasing such lock.

In testimony whereof, I affix my signature in the presence of two witnesses this twelfth (12th) day of February, 1915.

ADELMER M. BATES.
